UNITED STATES PATENT OFFICE.

WILLIAM E. SNAMAN, OF PITTSBURG, PENNSYLVANIA.

FLUSHING APPARATUS FOR WATER-CLOSET BOWLS OR HOPPERS.

941,283.

Specification of Letters Patent. Patented Nov. 23, 1909.

Application filed November 3, 1908. Serial No. 460,897.

To all whom it may concern:

Be it known that I, WILLIAM E. SNAMAN, a citizen of the United States of America, residing at Pittsburg, in the county of Allegheny and State of Pennsylvania, have invented certain new and useful Improvements in Flushing Apparatus for Water-Closet Bowls or Hoppers, of which the following is a specification, reference being had therein

10 to the accompanying drawing.

This invention relates to a flushing apparatus for water closet bowls or hoppers, and the object of my invention is to provide a novel apparatus for insuring a positive 15 flushing of a bowl or hopper, without creating a noise, a displacement of the mechanism, or failure of the mechanism to establish communication between the water contained within the tank and the flushing apparatus.

20 My invention aims to provide a combination "seat-action" and "pull-lever" apparatus that can be embodied within a tank for controlling the inlet of water to the tank and the discharge of the same. To this end, 25 I have provided in connection with a flush tank, a novel by-path for establishing a direct communication between the water in the tank and the down pipe thereof, whereby when the apparatus is actuated, an im-

30 mediate flushing will be accomplished without the slipping or dropping of a mechanism. Considerable trouble has heretofore been experienced with the flushing apparatus in this connection, often necessitating a second actuation of the apparatus to accomplish the flushing of a bowl or hopper, due principally to the fact that the valves controlling the passage of water between a tank and the bowl are not sufficiently opened to 35 allow the water to make headway and maintain the valves in an open position. Another defect, particularly in connection with "seat action" flushing apparatus, is a failure on the part of the apparatus to operate

40 due to the connection between the seat and the mechanism within the flushing tank, requiring oftentimes a considerable movement of the seat to properly place the flushing apparatus in operation.

45 My invention aims to obviate the above defects by the employment of a by-path, novel valves, and a simple and effective leverage mechanism for positively opening

and closing of valves to control the passage of water from the tank to the bowl or hopper. 55

An important characteristic of my invention are the valves which I employ in my preferred form, these valves being of a float type limited in movement by cages designed 60 for preventing accidental displacement of the valves, whereby the mechanism or pressure of water open the same.

With the above and other objects in view which will readily appear as the invention 65 is better understood, the same consists in the novel construction, combination and arrangement of parts to be described and then claimed.

In the drawings, Figure 1 is a vertical 70 sectional view of a flushing apparatus constructed in accordance with my invention, partly broken away, Fig. 2 is a longitudinal vertical sectional view of a flushing tank of a modified form, Fig. 3 is a plan of the same, 75 Fig. 4 is an elevation of a modified form of valve, Fig. 5 is a longitudinal vertical sectional view of the preferred form of tank illustrated in Fig. 1 of the drawings, Fig. 6 is a plan of the same, and Fig. 7 is a plan 80 of a modified form of tank.

In the accompanying drawings 1 designates a floor supporting a hopper or bowl 2 of the ordinary and well known type; upon the rear edge of this bowl is hinged, as at 3 85 a seat 4 and a lid 5. Above the bowl 2 are arranged brackets or other suitable support 6 for a flushing tank 7, this tank being made of a suitable water proof material. In some instances, the tank can be made of wood or 90 metal and suitably lined, as shown in Fig. 2, while in other instances, the tank can be made of porcelain or pottery ware, practically to reduce the expense of manufacturing the same in accordance with my invention and to present a neat and sanitary 95 appearance.

Assuming that the tank is made of porcelain, said tank adjacent to the bottom 8 thereof is provided with a horizontal partition 9 providing a by-path 10, this by-path centrally of the tank communicating with a down pipe or flush pipe 11 through the medium of an interiorly threaded nipple 12 into which the upper end of the down pipe 105 is threaded. The down pipe is provided

with a union coupling 13 and the lower end of said pipe connects with the bowl 2, as best shown in Fig. 1 of the drawings.

The horizontal partition 9 is provided 5 with a central opening 14 and surrounding this opening and extending upwardly into the tank is a cylindrical housing 15. The partition 9 between said housing and one end of the tank is provided with an inlet 10 opening 16, for admitting water from the tank to the by-path 10 and the housing 15. Arranged between the partition 9 and the bottom 8 of the tank is a transverse partition 17 closing one end of the by-path 10 15 from communication with the tank whereby an actuating rod 18 can extend upwardly through the by-path 10 and into the tank within a casing 19 forming part of one side of the tank. The lower end of the actuating 20 rod 18 is adapted to rest in a socket 20 provided therefor in the end of a rearwardly extending arm 21 carried by the seat 4 of the bowl 2.

The upper end of the rod 18 is adjustably 25 connected, as at 22 to a lever 23 arranged longitudinally within or at the rear of the tank and pivotally connected at one end to lugs 24 carried by the tank.

The inner sides of the tank 7 are provided 30 with bearings 25 for a rock shaft 26 having a cross arm 27. One end of this cross arm 27 extends over the housing 15 and is provided with a curved guide 28 and a depending chain or cable 29. Upon the lower end 35 of the chain or cable 29 is a cage 30 for a spherical float or ball 31 which may be termed generally a by-path valve adapted to seat upon the nipple 12 and shut off the communication between the by-path 10 and 40 the down pipe 11.

The opposite end of the cross arm 27 is provided with a curved guide 32 and with a depending chain or cable 33. Connected to the lower end of the chain or cable 33 is an 45 oblong cage 34 for a spherical float or ball 35, which may be termed generally a tank valve, this float being normally supported by an annular seat 36 forming part of the cage 34. The float 35 is adapted to normally 50 close the inlet opening 16, and the object of the annular seat 36 is to prevent water within the tank from accidentally displacing said float.

The cross arm 27 is provided with a right 55 angular extension 37 extending over the free end of the lever 23, this free end of the lever having a detachable counter weight 38 for a purpose that will hereinafter appear. Engaging under the extension 37 of the cross 60 arm 27 is the beveled end 39 of a lever 40 fulcrumed between brackets 41 carried by one end of the tank. This lever, together with the lever 23 and cross arm 27, are above the water level of the tank, and the said

lever 40 is adapted to protrude from the end 65 of the tank whereby said lever can be actuated by a chain or cable connected thereto.

The tank 7 is provided with a suitable water inlet pipe having a valve 42 controlled by a spherical float 43 connected by a rod 70 in the usual manner with said valve for opening and closing the same. This valve and float is of the ordinary form used with the present type of flushing apparatus.

The operation of my apparatus as above 75 described, is as follows: The movement of the seat 4 relative to the bowl 2 is sufficient when the seat is depressed, to elevate the rod 18, but the movement of said seat is hardly perceptible to a person lowering the 80 same. When the rod 18 is elevated, the lever 23 is raised, together with the extension 37 of the arm 27, causing the shaft 26 to rock. The long leverage of the lever 23 actuates the mechanism with a very slight 85 movement of the seat 4. When the arm 27 is rocked, the float 31 is lowered, to seat on the nipple 12 and close the outlet, and the float 35 is elevated to open the opening 16; the water within the tank 7 can then 90 flow through the opening 16 into the by-path 10 and into the housing 15 until it assumes a level within the housing 15 and the tank 7. It is impossible for the water within the by-path 10 to displace the ball 31 95 as said ball is confined within the cage 30, but the inrush of water through the opening 16 immediately gives the float 35 sufficient impetus to rise within the cage 34 and the float is confined within this cage until the 100 water within the tank 7 and the housing 15 recedes. When the seat is relieved of the weight of a person the detachable weight 38 of the lever 23 immediately lowers said lever and the rod 18 and elevates the seat 4 to its 105 normal position. The lowering movement of the lever 23 immediately lowers the cage 34 and elevates the cage 30 carrying with it the float 31. The water within the by-path 10, housing 15, and tank 7 is placed in communication with the down pipe 11 and will 110 immediately drain into the bowl 2 flushing the same. The float 35 which has been floating in the cage 34 gradually descends as the water lowers and closes against the opening 115 16. Simultaneously with the lowering of the float 35, the float 43 is lowered and upon reaching a certain position within the tank, it opens the valve 42 allowing water to enter the tank 7. This fresh supply of water 120 cannot enter the housing 15, as the float 43 closes the valve 42 upon reaching a certain elevation, and neither can the fresh supply of water affect the float 35 as the seat 36 shields the float 35 against such lateral displacement as would allow the water to pass below the float 35 and so make the pressure 125 on it uniform and start its buoyant action.

When the lever 23 is actuated by the rod 18, the lever 40 is inactive, but this lever can at any time be used for elevating the extension 37 and actuate the floats 31 and 35.

5 A modification of my invention is shown in Fig. 7 of the drawings, wherein the casing 19 is dispensed with, and the lever 23, rod 18, and lever 40 are arranged outside the tank, preferably at the rear thereof, sufficient space being provided between the tank and the wall or other support to provide a clearance for said levers. In this instance, the extension 37 extends through an opening 44 provided therefor in the rear wall of the tank. The housing 15 can be made an integral part of the rear wall of the tank and the opening 16 and the nipple 12 arranged in accordance therewith.

Reference will now be had to Figs. 2 and 20 3 of the drawings, wherein I have illustrated the bypass 10 and the housing 15 as a detachable part of the tank, permitting of my apparatus being installed in the present type of tank. In this construction, the 25 casing constituting the bypass and housing is made of light and durable metal or similar material and is located upon the bottom of the tank 45, said tank having a suitable lining and a down pipe connection 46.

30 In lieu of the spherical floats 31 and 35, I use tapering plugs or valves 47 and 48, the former being adapted to seat in the bottom of the tank 45 and close the down pipe connection, while the latter closes the opening 35 16 of the bypass. In connection with the detachable bypass 10, I use a siphon 49 having one end communicating with the bypass and the opposite end extending in proximity to the bottom of the tank. The 40 casing 19 in this instance is also detachable whereby it can be secured to the bottom of the tank according to where the rod 18 enters said tank. The lever 23 and the remainder of the mechanism is identical for moving 45 the plugs or valves 47 and 48.

The operation in connection with the detachable bypass is as follows: When the seat 4 is moved to rock the arm 27, the plug or valve 47 closes the down pipe connection 0 and the plug or valve 48 admits water through the opening 16 to the bypass and the housing carried thereby. Upon the seat being released, the plug or valve 47 is elevated and the plug or valve 48 is lowered. 5 The water within the bypass and the casing 15 passing into the down pipe immediately sets up a siphon action that causes the water within the tank to pass through the siphon 49 into the bypass 10, and down pipe to 0 the bowl 2.

In lieu of the cages 30 and 34, I can use a stirrup 50 as shown in Fig. 4 of the drawings.

The spherical floats 31 and 35 can be made

of rubber and hermetically sealed, whereby 65 said floats will have sufficient buoyancy to be effected by the volume of water contained within the tank.

I desire to call attention to the fact that the least upward movement of the seat 4 70 will immediately cause a communication to be established between the bypass 10 and the down-pipe and it is impossible for the mechanism to slip or trip and necessitate a second actuation of the seat. 75

Since rod 18 is not connected with the rearwardly-extending arm 21, but merely rests normally in engagement therewith, it will be evident that the seat may be raised at will to permit cleansing of the bowl, etc. 80

The cages 34 and 30 permit of the float valves revolving or shifting, whereby said float valves will be subjected to an even wear. The stirrup 50 is designed for the same purpose but not to that extent as the 85 cages 30 and 34.

While in the drawings forming part of this application there is illustrated the preferred embodiments of my invention, I would have it understood that the structural 90 details thereof can be varied or changed as to the shape, proportion and manner of assemblage, without departing from the spirit of the invention.

Having now described my invention what 95 I claim as new, is:

1. In a flushing apparatus, the combination with a bowl having a hinged seat, of a tank communicating with said bowl by a down pipe, said tank having a horizontal 100 partition formed therein adjacent to the bottom thereof and providing a bypass adapted to normally communicate with said bowl, a housing carried by said partition, said partition having a water inlet opening 105 formed therein, a casing arranged within said tank, a rod extending downwardly through said casing and adapted to be actuated by a lowering movement of said seat, a weighted lever pivotally mounted in said 110 tank and connecting with said rod, a transverse shaft journaled in said tank, a cross arm carried by said shaft and having an extension adapted to be engaged by said lever, a cage suspended from one end of said cross arm within said housing, a spherical float arranged within said cage and adapted to close the communication between said bowl and said bypass, a cage suspended from the opposite end of said cross arm, a movable spherical float arranged within said 115 cage and adapted to close the inlet opening of said partition, and a lever pivotally mounted in said tank and extending outside thereof for moving said cross arm independently of the first mentioned lever and the rod connecting therewith. 120

2. In a flushing apparatus, the combina-

tion with a bowl having a hinged seat, of a tank communicating with said bowl, a horizontal partition arranged in said tank and providing a bypath adapted to communicate with said bowl, a housing carried by said partition, said partition having an inlet opening formed therein establishing communication between said tank and said bypath, a lever pivotally mounted in said tank and adapted to be actuated by a movement of said seat, a cross arm fulcrumed within said tank and having an extension for engaging said lever, a cage suspended from one end of said cross arm within said housing, a spherical float arranged within said cage for controlling the communication between said bypath and said bowl, an oblong cage suspended from the opposite end of said cross arm, a movable spherical float arranged within said cage for controlling the communication between said tank and said bypath, and a lever pivotally mounted within said tank and extending outside thereof for moving said cross arm independently of the seat action of said bowl.

3. In a flushing apparatus, the combination with a bowl having a hinged seat, of a tank communicating with said bowl, a horizontal partition arranged in said tank and providing a bypath adapted to communicate with said bowl, a housing carried by said partition, said partition having an inlet opening formed therein establishing communication between said tank and said bypath, a lever pivotally mounted in said tank and adapted to be actuated by a movement of said seat, a cross arm fulcrumed within said tank and having an extension for engaging said lever, a cage suspended from one end of said cross arm within said housing, a spherical float arranged within said cage for controlling the communication between said bypath and said bowl, an oblong cage suspended from the opposite end of said cross arm, and a movable spherical float arranged within said cage for controlling the communication between said tank and said bypath.

4. In a flushing apparatus, the combination with a bowl having a hinged seat, of a tank communicating therewith, a horizontal partition arranged in said tank and providing a bypath, a confined spherical float for controlling the communication between said bypath and said bowl, a movable spherical float for controlling the communication between said tank and said bypath, a fulcrumed cross arm for alternately moving said floats, and a leverage mechanism actuated by the seat of said bowl for moving said cross arm.

5. The combination with a bowl having a seat action for controlling the admission of water to said bowl, of a tank, said tank hav-

ing a bypath formed therein adapted to communicate with said bowl, spherical floats for controlling the communication between said bypath and said bowl, and the said bypath and said tank, means for limiting the movement of said floats, and a leverage mechanism actuated by the seat action of said bowl for alternately moving said floats to first establish communication between said bypath and said tank and then establish communication between said bypath and bowl, whereby water can pass from said tank directly to said bowl.

6. A tank for flushing bowls, comprising in combination a bypath communicating with said bowl, alternately actuated floats controlling the communication between the bypath and the bowl and the communication between the bypath and the tank, and means for confining said floats, said means normally holding one of said floats while the other of said floats is permitted to move relative to the first mentioned float.

7. In a flushing apparatus, the combination with a bowl having a hinged seat, of a tank communicating with said bowl by a down pipe, said tank having a horizontal partition formed therein adjacent to the bottom thereof and providing a bypath adapted to normally communicate with said bowl, a housing carried by said partition, said partition having a water inlet opening formed therein, a casing arranged within said tank, a rod extending downwardly through said casing and adapted to be actuated by a lowering movement of said seat, a weighted lever pivotally mounted in the back of said tank and connecting with said rod, a transverse shaft journaled in said tank, a cross arm carried by said shaft and having an extension adapted to be engaged by said lever, a plug suspended from one end of said cross arm within said housing and adapted to close the communication between said bowl and bypath, a cage suspended from the opposite end of said cross arm, a movable spherical float arranged within said cage and adapted to close the inlet opening of said partition, and a lever pivotally mounted in said tank and extending outside thereof for moving said cross arm independently of the first mentioned lever and the rod connecting therewith.

8. In a flushing apparatus, a tank, a bypath therein, a tank valve normally closing the by-path against the flow of water from the tank whereby the by-path is normally empty, the outlet for the water from said tank being through said by-path, a by-path valve normally unseated whereby the outlet from the by-path is normally open, a rock shaft carried by the tank, a cross arm carried by said rock shaft, connections between the ends of said cross arm and the tank

valve and by-path valve respectively, an extension carried by said cross arm and extending at right angles thereto, and a pivoted lever carried by the tank having its
5 free end underlying the said extension of the cross arm for engagement therewith when actuated to operate the valves.

In testimony whereof I affix my signature in the presence of two witnesses.
